ATTORNEY.

UNITED STATES PATENT OFFICE.

CLARENCE LILE, OF GRANITE CITY, ILLINOIS.

NOTE HOLDER AS NEW ARTICLE OF MANUFACTURE.

Application filed March 11, 1926. Serial No. 93,946.

My invention relates to an article of manufacture and is directed more particularly to such an article that can be used advantageously for holding paper sheets containing notes or memoranda.

The primary object of the invention is to provide an article of manufacture for use such as a note holder whereby the housewife may apprise the milkman or other delivery man of her household needs without the necessity of oral instructions. As is well known, milk deliveries are made in metropolitan districts principally during the night or very early hours of the morning, and any variation in the customary standing instructions must be conveyed to the milkman by means of a note or written order. If such a note is merely slipped into an empty bottle or placed under the bottle, it very often becomes lost with the result that the special order is not supplied; and to obviate this difficulty, I have provided a note-holder comprising a shank in two components between which the note may be gripped, the note-holder being then dropped into the mouth of the bottle where it is held by a loop-shaped handle.

These advantages, as well as others, will be better apparent from a detailed description of the invention in connection with the accompanying drawings, in which:

Fig. 1 is a side elevation of the note-holder carrying a note and inserted in a milk bottle (shown dotted); Fig. 2 is a side elevation of the note-holder with the note removed; and Fig. 3 is an elevational view taken at right angles to Fig. 2 with a note in place in the holder.

Referring to the drawings, *w* represents a piece of wire bent at one end in the form of a loop 1 which constitutes the handle of the holder, the wire then extending downwardly from the handle 1 to form one component 2 of a shank 3, the shank having a second component 4 bent back onto the component 2, the components 2 and 4 being twisted together at 5 just above the terminal bend or eye 6. The shank component 4 ter-

minates at its inner end in an open ring 7 spaced, along the component 2, a short distance from the loop 1, and the component 2 is provided with a kink 8 opposite the ring 7 and projecting a short distance into said ring. The gap 9 in the ring 7 allows the crease *c* in the note *n* to readily pass beyond the ring 7 when the note is forced between the components 2 and 4. On moving the note *n* to the dotted position (Fig. 3), it is securely held in place, being pinched into the ring 7 by the kink 8.

It is apparent from Fig. 1 that the milkman cannot take up the empty bottles without encountering the handle 1 of the note-holder should the note-holder be within the bottle; consequently, there is no occasion for him to overlook the note. After he has noted his instructions and supplied the order, he slips the loop comprising the handle 1 of the note-holder over the neck of a bottle as shown (dotted) in Fig. 1.

Having described my invention, I claim:

1. An article of manufacture comprising a shank of substantial length and capable of insertion into a bottle, said shank having two components twisted together for part of their length, and each terminating in an eye, one of said components extending beyond the other, and having a kink bent into it intermediate its ends, said kink lying adjacent to the eye in the shorter component and entering slightly therein.

2. As a new article of manufacture, a device for holding sheets of paper comprising a shank of substantial length and capable of insertion into a bottle, said shank formed of two components in closely spaced relation, one of said components having a kink formed in it at an intermediate point, and the other component terminating in an open eye in opposed relation to said kink, said eye and kink being adapted to cooperate for holding a sheet of paper, and a handle at one end of said shank.

In testimony whereof I hereunto affix my signature.

CLARENCE LILE.
